 2 Claims. (Cl. 170—145)

ABSTRACT OF THE DISCLOSURE

A paddle wheel apparatus for propelling a boat through water where the individual paddles of the paddle wheel or drum move substantially radially inwardly and outwardly of the paddle wheel as it rotates whereby the paddles extend outwardly substantially their full length from the paddle wheel as they drive through the water but are slid inwardly into the wheel as they rotate. The paddles are journaled to a fixed shaft mounted eccentrically within the paddle wheel and extend through axially directed slots in the body of the paddle wheel.

This invention relates to a propulsion device for a boat or the like, the propulsion device being basically of the paddle wheel type. The novel feature of the propulsion device is that the individual paddles of the paddle wheel are not mounted to the body of the paddle wheel itself, but instead are journaled on a fixed shaft which is eccentrically mounted within the body of the paddle wheel. Each of the separate paddles or paddle means extend through a respective axially directed slot in the body of the paddle wheel so that as the body rotates, the paddle means are caused to be slid radially outwardly of their respective slots as they rotate and drive through the water and radially inwardly of their respective slot to withdraw into the body of the paddle as they rotate.

Such a feature of the paddle means being caused to be slid almost their full length in and out of their respective slots as the paddle wheel rotates efficiently cleans the paddle wheel as it operates so that the propulsion device of the invention is particularly adapted for boats to be used in marshy or swamp areas.

For a better understanding of the propulsion device of the invention, reference should be had to the accompanying drawing, wherein:

FIG. 1 is a partially broken-away, front elevation of a preferred embodiment of the apparatus of the invention;

FIG. 2 is a fragmentary, end elevation, with parts shown in cross section, of the paddle wheel of the propulsion device, particularly illustrating the fixed shaft eccentrically mounted within the body of the paddle wheel and the paddle means journaled to the fixed shaft extending through respective slots in the body of the paddle wheel;

FIG. 3 is a fragmentary elevation of the fixed shaft, particularly illustrating the manner in which the individual paddle means are journaled on the fixed shaft; and

FIG. 4 is a side elevation, similar to FIG. 1, illustrating another embodiment of the apparatus of the invention.

Now referring to the drawings in greater detail, and with particular reference to FIG. 1, the numeral 10 generally illustrates the propulsion device of the invention. The propulsion device may be used to drive a variety of articles, but it is particularly adapted to drive a boat 12, for example, in marshy or swamp areas.

The propulsion device 10 consists of a pair of supports 14 which usually extend downwardly and rearwardly from the boat and which are secured as by bolts 16 to a part of the boat 12. Both of the supports 14 are provided with a suitable end block portion 14a and a hollow drum on sleeve 18 extends between the end block portions 14a of the supports 14 and is journaled thereto by suit-

able bearings 20. As will be explained in greater detail hereinafter, the sleeve or drum 18 serves as the body of the paddle wheel utilized in the propulsion device of the invention.

As is best illustrated by FIG. 2, the sleeve 18 which serves as the body of the paddle wheel is hollow and it is provided with an annular gear wheel or gear means 22 about its peripheral surface at about the center portion thereof. The gear wheel or gear means 22 may be cut or suitably formed in the drum 18 on its peripheral surface. A suitable motor 24 is secured to the stern of the boat 12 and suitable means such as a worm gear 26 is provided to engage the wheel gear 22 for drive by drive shaft 28 of the motor 24. In this manner, actuation of motor 24 to rotate drive shaft 28 and worm gear 26 effects a rotation and drive of the sleeve 18.

Also extending between the end block portions 14a and being mounted in substantially fixed relationship thereto is a shaft 30. As is best illustrated by FIG. 2, fixed shaft 30 extends through sleeve 18 and is mounted to end block portions 14a in eccentric relationship with the sleeve 18. As is best illustrated by FIG. 3, a plurality of paddles or paddle means 32 are separately and individually journaled to the fixed shaft 30. Each of the paddle means 32 is provided with at least one paddle bearing 34 which secures its respective paddle means 32 to the shaft 30 but yet permits the paddle means 32 to rotate about the fixed shaft 30. As is best illustrated by FIG. 2, each of the paddle means 32 extend generally radially from the fixed shaft 30 and extend through a respective axially directed slot 36 provided in the periphery of the sleeve 18.

Due to the fact that each of the paddle means 32 extends through a respective slot 36 in the sleeve 18, the paddle means are caused to be rotated with the sleeve 18 as it is driven by motor 24. But, as can be seen by FIG. 2, the fact that the paddle means 32 are journaled to fixed shaft 30 which is eccentrically mounted within the sleeve 18 causes the paddle means 32 to move substantially inwardly or outwardly in their respective slots 36 as the sleeve 18 is driven. For example, referring to FIG. 2, it can be seen that as the sleeve 18 is rotated, the paddle means passing through the uppermost portion of the arc, for example, paddle means 32a, is moved radially inwardly in its respective slot 36 until only a small portion, if any, of the paddle means 32a extends above the peripheral surface of the sleeve 18. Similarly, as the paddle means 32 rotate through the bottommost portion of their arc, as, for example, paddle means 32b, the paddle means extend substantially their entire length out of respective slots 36. As the paddle means 32 pass between the extreme position indicated by paddles 32a and 32b, they take the positions indicated by paddle 32c and 32d wherein paddle means 32c, for example, begins to move and/or slide radially outwardly of its respective slot 36 on its way toward occupying the fully extended position indicated by paddle means 32b. Paddle means 32d, contrarily, begins to move radially inwardly of its respective slot on its way to occupying the fully withdrawn position indicated by paddle means 32a.

As is illustrated by FIG. 2, it is seen that the arcuate distance between the adjacent paddle means 32 does not remain constant as the sleeve 18 is rotated through one revolution. For example, referring to FIG. 2, the arcuate distance between paddle means 32a and 32c will change considerably as paddle means 32c is rotated to occupy the fully extended position indicated by paddle means 32b. The separate paddle bearings 34 of each paddle means 32 allows such independent movement and rotation of the paddle means with relation to each other.

As indicated diagrammatically by FIG. 2, the lower portion of the sleeve 18 which forms the body of the

paddle wheel of the propulsion device extends down into water 40 as the propulsion device of the invention actually operates. It thus can be easily seen that as the paddle means are rotated through the water 40 they are in their fully extended position to achieve maximum drive, but wherein as they are rotated above the water they are withdrawn almost fully into the sleeve 18. The purpose of such a novel arrangement is to provide for a self-cleaning of the paddle means 32 so that if the paddle means 32 pick up any weeds as they drive through the water 40, such weeds will be cleaned off of the paddle means as they are withdrawn into the sleeve 18. Such self-cleaning action readily adapts the propulsion device of the invention for boats used in swamp or marsh areas.

FIG. 4 illustrates a modification of the propulsion device indicated by FIG. 1 wherein a slightly different paddle wheel is utilized along with a different drive means therefor. Referring to FIG. 4, boat propulsion device 10a is secured to a boat 12a. Similar to the embodiment of FIG. 1, the boat propulsion device is comprised of a pair of supports 14b which are secured to and extend in a rearwardly direction from part, probably the stern, of the boat 12a. Journalled to the supports 14b is a hollow sleeve 18a which is adapted to be driven by a motor 24a, usually secured to the stern of the boat 12a. A pair of drive shafts 28a from the motor 24a drive a pair of beveled gear assemblies 42 which include a shaft 28b extending down through the supports 14b to engage with and drive sleeve 18a by pinion and ring gear means 39.

In this embodiment, a fixed shaft 30a is mounted to the supports 14b in an eccentric relationship with the sleeve 18a. The shaft 30a has a pair of paddle means 44 independently and separately journalled thereto, which paddle means extend through respective slots 36a in the sleeve 18a. In a manner similar to the manner hereinbefore described, rotation of the sleeve 18a by motor 24a causes paddle means 44 to be moved radially outwardly of their respective slots to a fully extended position as they pass through the water, and to move radially inwardly to a fully withdrawn position as they pass above the water.

It should be noted that in the embodiments illustrated by FIGS. 1 and 4, respectively, the fixed shafts 30 and 30a are secured to a suitable plate 50 and 50a, respectively, which are adjustably mounted to the supports 14 and 14b by suitable bolts 52 and 52a which extend through slots (not shown) in supports 14 and 14b, respectively. Such an arrangement allows the position of the fixed shafts 30 and 30a to be adjusted so that the eccentric relationship between fixed shaft 30 and the sleeve 18, and fixed shaft 30a and sleeve 18a can be selectively controlled.

While in accordance with the patent statutes only one best known embodiment of the invention has been illustrated and described in detail, it is to be particularly understood that the invention is not limited thereto or thereby, but that the inventive scope is defined in the appended claims.

What is claimed is:

1. A propulsion device for a boat comprising a pair of spaced-apart supports secured to the boat, and connected by horizontally extending member attached to the upper end of the supports, a hollow sleeve extending between said supports, means for rotatably supporting said sleeve in said supports, said sleeve having a plurality of peripherally and axially extending slots therein, a fixed shaft extending within the sleeve, means secured to each of the supports for receiving the free ends of the shaft, said means consisting each of a plate adjustably positionable in the aforesaid supports to vary the eccentric relationship between the fixed shaft and the sleeve in a vertical direction and radially of the sleeve, a motor carried by the horizontally extending member at the center thereof, means connecting said motor to the sleeve to cause rotation thereof, and a plurality of paddles journalled for rotation on said fixed shaft, each of the paddles extending through a slot in the sleeve, whereby rotation of the sleeve effects rotation of the paddles, the connecting means between the motor and the sleeve consisting of a ring gear secured to the sleeve on the outer periphery thereof and medially of the end faces thereof, and drive means driven by the motor and meshing with said ring gear.
2. A propulsion device for a boat comprising a pair of spaced-apart supports adapted to be secured to the boat to provide vertically extending sections, a hollow sleeve extending between said supports, means for rotatably supporting said sleeve on said supports, said sleeve having a plurality of axially extending slots therein extending substantially the length thereof, a fixed shaft extending within the sleeve, means secured to said sections of each of the supports for receiving the free ends of the shaft, said means consisting essentially each of a plate vertically adjustably positionable in the aforesaid supports to vary the eccentric relationship between the fixed shaft and the sleeve in a vertical direction and radially of the sleeve, means to secure said plates in fixed positions on said sections, the boat being adapted to position a motor thereon, a means for connecting a said motor to the sleeve to cause rotation thereof, and a plurality of paddles journalled for rotation on said fixed shaft, each of the paddles extending through a slot in the sleeve, whereby rotation of the sleeve effects rotation of the paddles, the means for connecting the motor and the sleeve including a ring gear operably secured to the sleeve, and drive means drivable by the motor and engaging said ring gear.
